(57) **CLAIM**

The ornamental design for a telescopic rod for vehicle chair, as shown and described.

DESCRIPTION

FIG. 1 is a perspective view of the telescopic rod for vehicle chair showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a partial enlarged view of portion 8 in FIG. 1; and, FIG. 9 is an enlarged view of portion 9 in FIG. 1.

The dash-dash broken lines shown in FIGS. 1-8 illustrate portions of the telescopic rod for vehicle chair that form no part of the claimed design. The dot-dash broken lines surrounding the detail views shown in FIGS. 1 and 8 are for annotative purposes only and form no part thereof.
